UNITED STATES PATENT OFFICE.

SAMUEL V. REEVES, OF HADDONFIELD, NEW JERSEY.

AUTOMATIC DUST-DAMPER FOR STOVES.

1,156,930.

Specification of Letters Patent.

Patented Oct. 19, 1915.

Continuation of application Serial No. 852,349, filed July 22, 1914. This application filed August 9, 1915.
Serial No. 44,422.

To all whom it may concern:

Be it known that I, SAMUEL V. REEVES, a citizen of the United States, residing at Haddonfield, county of Camden, State of New Jersey, have invented a new and useful Automatic Dust-Damper for Stoves, of which the following is a specification.

In a prior application filed by me on July 22nd, 1914, Serial No. 852,349, of which this, 10 in its broad aspects, is a continuation, I have described and broadly claimed a novel construction of a stove wherein the parts thereof are adapted either for a right or left-hand arrangement of the stove.

15 In my present invention I have devised a novel automatic dust damper wherein when the grate shaker is placed in position to operate the grate, the dust damper is automatically opened and when the shaker is removed the damper automatically closes.

It further consists of a novel construction and arrangement of damper adapted to be employed with either a right or left-hand arrangement of the parts of the stove and 20 novel means for actuating the damper, the parts being constructed in such a manner that they return to their initial or normally closed position due to the force of gravity.

Other novel features of construction and 25 advantage will hereinafter more clearly appear in the detailed description of my invention.

For the purpose of illustrating my invention I have shown in the accompanying drawings one form thereof which is at present preferred by me, since the same will give in practice satisfactory and reliable results; although it is to be understood that the various instrumentalities of which my 30 invention consists can be variously arranged and organized and that my invention is not limited to the precise arrangement and organization of these instrumentalities as herein shown and described.

40 Figure 1 represents a sectional elevation of a stove in conjunction with which an automatic dust damper embodying my invention is employed. Fig. 2 represents a sectional view on line α — α Fig. 1. Fig. 3 represents a sectional elevation showing the damper as assembled with respect to a right-hand arrangement of the stove. Fig. 4 represents a perspective view of the damper and operating means in detached position. Fig.

5 represents an elevation of the counterbalance employed. Fig. 6 represents a plan view of the damper in detached position. Fig. 7 represents a plan view of a damper guide. Figs. 8, 9 and 10 represent elevations of details of the construction. Fig. 11 represents a side elevation of a modified form of actuating arm. Fig. 12 represents a front elevation of a portion of my device.

Similar numerals of reference indicate corresponding parts in the figures.

Referring to the drawings, I have preferred to illustrate my invention in connection with a stove constructed in accordance with my copending application to which I have hereinbefore referred but it is of course to be understood that my invention is not limited to use with such type of stove but may be employed in conjunction with any other desired or conventional type of stove mechanism.

It will be further understood that any desired form of grate may be employed either of the draw-bar or rocking type and for purposes of illustration I have shown in Fig. 2 a grate of the draw-bar type.

1 designates an ash pit which communicates by means of an opening 2 with the dust flue 3 carried by the rear plate 4 of the stove and communicating with the smoke-pipe 5. In order that the damper 85 may be employed with either a right or left-hand arrangement of the parts of the stove, a flue 6 is employed corresponding in construction to the flue 3 and having an opening 7 in the rear plate 4 which is closed by 90 means of a cover when the left-hand arrangement of the parts is employed.

8 designates the dust damper which is provided with an outwardly extending arm 9 having a plurality of spaced apertures 10 therethrough and provided with a post or lug 11 the outer end of which has a polygonal contour, as at 12, and, in the present instance, such end is shown as being rectangular. The post 11 is provided with an aperture 13 adapted to receive a cotterpin 14 and the side of the damper 8 opposite the post 11 is provided with a dowel pin 15.

16 designates a link having near one end thereof a polygonal shaped opening 17 which, in the present instance, is made rectangular in order to be received on the rectangular end 12 of the post 11. The end

12 is provided with an aperture 18 through which is adapted to pass a fastening device such as, for example, a cotterpin 19 in order to maintain the parts in assembled position. The opposite end of the link 16 is provided with a plurality of spaced apertures 20 through a desired one of which is adapted to pass a fastening device 21 such as, for example, a cotterpin, said pin also passing through one of the longitudinally spaced apertures 22 of a link 23. The opposite end of said link 23 is provided with a plurality of longitudinally spaced apertures 24 through which is adapted to pass a fastening device, such as for example, a cotterpin 25, which also passes through one of the longitudinally spaced apertures 26 at the end of the extension 27 of a rod 28. The rod 28 passes through one of the apertures 29 in the rear plate of the stove and also through one of the apertures 30 in the front plate 31 of the stove and its outer end is adapted to be connected with an arm 32 in any desired manner. In the present instance I have shown this as being accomplished by having the end of the rod 28 in threaded engagement with the arm 32 and fixed in position by means of a pin 33 passing through said arm and rod. The arm 32 terminates in a lateral extension 34 which rests upon or in close proximity to the outer end of the grate actuating member 35, illustrated as a draw-bar.

36 designates a weight or counterbalance 35 having a recess 37 adapted to receive the dowel pin 15 of the damper 8 and the counterbalance is provided at its outer end with spaced apertures 38 located at opposite sides of the counterweight.

40 39 designates a fastening device, such as for example a bolt and nut, the bolt being adapted to pass through predetermined apertures 10 and 38, in order to maintain the counterweight 36 in assembled condition 45 with respect to the damper 8. The rear plate 4 of the stove is provided in proximity to each dust flue 3 and 6 with an opening 40 adapted to receive a dowel pin 41 carried by a guide 42 which latter is secured to the rear plate 4 by means of a fastening device 43 passing through one of the apertures 44 in the rear plate 4 of the stove.

The guide bracket or plate 42 is provided with an off-set portion 45 thereby forming a shoulder 46 in proximity to which the damper 8 travels and the off-set portion 45 forms a flange to guide the damper during its movement.

In some cases the actuating arm 47, seen in Fig. 11, may be employed and provided with a deflected rounded portion 48 adapted to fit over the actuating member of the grate such as, for example, the draw-bar, shaker bar or their equivalents.

65 The movement of the damper 8 toward its

closing position is limited by means of a lug 49 connected with or forming a part of the rear stove plate 4.

In the operation of my device, assuming that the parts are constructed as seen in Fig. 70 4, the portion 34 of the arm 32 rests upon or in close proximity to the grate actuating member 35.

When the shaker implement is placed on the grate actuating member 35 it will slide 75 between the lateral extension 34 and the draw-bar or actuating member of the grate thereby causing the arm 32 to rock the rod 28 and through the co-operation of the links 23 and 16 the damper 8 will be swung downwardly.

Owing to the provision of the counterbalance 36 the damper will return to its initial or closed position as soon as the grate actuating element is removed from the grate 85 actuating member.

The construction of the end of the damper actuating arms, such as 32 or 47, may be constructed in any desired manner and located either interiorly or exteriorly of the 90 stove, and the end thereof in proximity to the grate actuating bar will vary in accordance with the construction of such bar.

It will be apparent from Figs. 1, 3 and 4 that the damper may be readily adjusted 95 for either a right or left-hand arrangement of the parts, and in Fig. 1 the parts are shown with a left-hand arrangement of the stove, while in Fig. 3 the parts are shown in the positions they assume with a right-hand arrangement of the parts.

The amount of movement imparted to the damper may be readily varied by adjusting the fastening devices 25 or 21, it being noted that in the form illustrated, a plurality of 105 apertures are provided in the link 23 with which such fastening devices are adapted to co-operate so that the length of stroke of the damper 8 may vary in accordance with the conditions and requirements met with in 110 practice.

It will be apparent from the foregoing that the damper is normally maintained in closed position by means of a counterbalance and means are employed operatively connected with the damper and extending in proximity to the grate actuating member whereby when the shaking element or implement is assembled with respect to the grate actuating member it will effect the operation 115 120 of the latter and cause the damper to open communication by means of the flue opening with the ash pit and the exhaust flue leading to the smoke pipe of the stove.

Attention is directed to the fact that the 125 parts of the damper mechanism are constructed in such a manner that they can be arranged for either a right or left-hand arrangement of the damper. I also provide means to limit the movement of the damper 130

on its return movement so that the damper will be maintained in closed position at all times except when it is desired to shake the grate.

5 Attention is also directed to the manner in which the various parts are constructed in order that the amount of movement imparted to the damper may be varied as desired.

10 I have preferred to show a portion of the damper mechanism located within and a portion located without the stove, but it will be apparent that the entire damper mechanism may be located either interiorly 15 or exteriorly of the stove and still be within the scope of my invention.

It will further be apparent that, if desired, I may dispense with the counterbalance 36, since the parts connected with the 20 damper may have the desired weight to effect the return of the parts to their normal position or the arm, such as 32 or 47, may be weighted in order to accomplish this purpose, it being seen that in such event, the 25 parts of the damper are returned to their initial or normal position, due to force of gravity. The portion of the actuating arm extending in proximity to the grate preferably is of a contour conforming to the 30 contour of the end of the actuating member of the grate.

It will be apparent that my device may be used in connection with any desired type 35 of a grate, in which a member is provided to effect the shaking thereof and the passage of the ashes into the ash pit.

It will now be apparent that I have devised a novel and useful construction of an 40 automatic dust damper for stoves which embodies the features of advantage enumerated as desirable in the statement of the invention and the above description, and while I have, in the present instance, shown and described a preferred embodiment thereof which will 45 give in practice satisfactory and reliable results, it is to be understood that the same is susceptible of modification in various particulars without departing from the spirit or scope of the invention or sacrificing any 50 of its advantages.

Having thus described my invention, what I claim as new and desire to secure by Letters Patent, is:—

1. The combination with the ash pit, the 55 dust flue, and the actuating member of a grate, of a damper controlling said flue, a counterbalance for said damper, and an arm operatively connected with said damper and in proximity to said member, whereby upon 60 the assembling of a shaker element with said member said damper will be moved to open communication between said ash pit and dust flue.

2. The combination with the ash pit, the 65 dust flue, and the actuating member of a

grate, of a damper controlling said flue, a counterbalance for said damper, and an arm operatively connected with said damper and in proximity to said member, whereby upon the assembling of a shaker element with said member said damper will be moved to open communication between said ash pit and dust flue, and said counterbalance effecting the return of said damper to its initial or closed position. 70

3. The combination with the ash pit, the dust flue, and the actuating member of a grate, of a damper controlling said flue, a counterbalance for said damper, an arm operatively connected with said damper and in proximity to said member, whereby upon the assembling of a shaker element with said member said damper will be moved to open communication between said ash pit and dust flue, said counterbalance effecting the return of said damper to its initial or closed position, and means to stop said damper on its return movement to its initial position. 75

4. The combination with the ash pit, the dust flue, and the actuating member of a 80 grate, of a damper controlling said dust flue, an arm in proximity to said member and adapted to be moved by the assembling of a shaker element with said member, and means to operatively connect said arm to said 85 damper to effect a right or a left hand arrangement of said damper, and the movement of said arm effecting the opening of said damper. 90

5. The combination with the ash pit, the 95 dust flue, and the actuating member of a grate, of a damper controlling said flue, a counterbalance for said damper, and an arm operatively and adjustably connected with said damper and in proximity to said member, whereby upon the assembling of a shaker element with said member said damper will be moved to open communication between said ash pit and dust flue. 100

6. The combination with the ash pit of a 110 stove, an exhaust flue communicating therewith, and the actuating member of a grate, of a damper controlling said flue, and means in proximity to said member for actuating said damper whereby when a shaking implement is assembled with said member it will be brought into engagement with said means to move the same and actuate the damper. 115

7. In a stove, the combination with the 120 rear plate contributing to form an ash pit and having a flue opening communicating with the ash pit, and with the grate actuating member, of a damper pivoted to said plate, a counterbalance for said damper to normally maintain it in closed position, a 125 guide for said damper, a link adjustably connected with said damper, a rod connected with said link, and an arm on said rod and extending into proximity to the grate actuating member. 130

8. In a stove, the combination with the rear plate contributing to form an ash pit and having a flue opening communicating with the ash pit, and with the grate actuating member, of a damper pivoted to said plate, a counterbalance for said damper to normally maintain it in closed position, a guide for said damper, a link adjustably

connected with said damper, a rod adjustably connected with said link, and an arm on ¹⁰ said rod and extending into proximity to the grate actuating member.
